Patented June 30, 1914.

UNITED STATES PATENT OFFICE.

HENRY E. GUYER, OF MARCELINE, MISSOURI.

RAIL-BRACE.

1,102,044.

Specification of Letters Patent. Patented June 30, 1914.

Application filed July 22, 1913. Serial No. 780,523.

To all whom it may concern:

Be it known that I, HENRY E. GUYER, citizen of the United States, residing at Marceline, in the county of Linn and State of Missouri, have invented certain new and useful Improvements in Rail-Braces, of which the following is a specification.

This invention relates to an improvement in rail-braces.

10 The primary object of the invention is to provide a rail-brace for supporting the guide rail in proper spaced relation with respect to the frog.

15 A further object of the invention is to construct a brace of this character the terminals of which will contact with the tie-plate as well as the base, web and tread of the rail.

20 A further object of the invention is to provide a construction in which the sections which constitute the brace may be readily positioned between the frog and rail by which they may be held against movement, thus maintaining the proper gage between the rails.

25 For a full understanding of the invention reference is to be had to the following description and accompanying drawing, in which:

Figure 1 is a top plan view. Fig. 2 is a sectional view showing the braces employed with a plurality of adjacent rails. Fig. 3 is a section on the line 3—3 of Fig. 1. Fig. 4 is a section on the line 4—4 of Fig. 1, and Fig. 5 is a perspective view of the rail-engaging terminal of one of the sections of the brace.

Corresponding and like parts are referred to in the following description and indicated in all the views of the accompanying drawing by the same reference characters.

In the drawings 10 designates the brace which consists of the sections 11 and 12. Each of the sections 11 and 12 is substantially semi-circular in cross-section, their 45 meeting terminals being secured together in any suitable manner and to the tie 13. In the form shown in the drawing the section 12 is formed with a slot and the section 11 with a tongue which enters said slot. The 50 slotted portion of the section 12 is formed with an opening 15 which aligns with the opening formed in the tongue of the section 11 whereby a bolt or lag-screw may be inserted. The rail-engaging terminal of each section 55 is enlarged, its end-portion 16 being of a height slightly less than the height of the

rail. These enlarged terminals 17 are recessed as at 18 whereby they may embrace the edge 19 of the tie-plate 20. The terminal is cut obliquely at 21 and contacts with the sloping face of the rail-base. When the braces contact with the rails at the point where the bolts project through the web portions the ends of the sections are formed with recesses 22 to receive the bolt-heads or 60 the nuts which are arranged on the bolts, thus allowing the portion 23 of the terminals to contact with the web of the rail and providing an effectual nut-lock when the nut-receiving end of the bolt is positioned in the 65 recess 22. The terminals are again reduced as at 24 in order that they may partially embrace the side walls 25 of the tread of the 70 rail.

Attention is called to the fact that the end 75 of each of the sections contacts with the rail throughout its entire height and that the rail as well as the plate on which the same is mounted will be effectually supported against lateral movement. Each of the sections is provided with an aperture 26 adjacent its enlarged terminal which receives a securing spike that is driven into the ties. The sections are thus supported against 80 separating at their inner terminals and effectually held against movement transversely of the tie adjacent their rail-engaging 85 terminals.

The many advantages of a construction of this character will be clearly apparent, as it 90 will be noted that the construction provides an effectual brace for spacing the frog and the guard rail on the tie and which is supported against movement transversely of the same. It will also be noted that the sections 95 may be easily and economically manufactured and that their rail engaging terminals may be recessed to embrace fish-plates or rails of various designs. It will also be seen that in instances where the rail-engaging 100 terminals embrace the securing bolts of the rails the bolts effectually prevent movement of the end portions of the sections longitudinally of the rails and thus slipping of the sections at the point where they engage the rails is prevented.

Having thus described the invention what is claimed as new is:

1. A rail-brace including a plurality of sections each of the sections being formed with an enlarged rail-engaging terminal recessed to embrace the tie-plate and provided

with an obliquely cut face disposed to contact with the rail-base, the terminals being formed with bolt-receiving openings and recessed above said openings to partially embrace the tread of the rail.

2. A rail brace including a pair of bars, a tongue formed integral with one of said bars and extending within a groove formed in the other bar, the grooved portion of the first mentioned bar being formed with an opening alining with an opening formed in the tongue of the other bar, each of the bars having an enlarged terminal recessed to embrace the tie-plate and formed with a sloping face adjacent said recess which contacts with the base of the rail, there being an opening formed in the terminal which em-

braces the nut arranged on the securing bolt which passes through the rail.

3. A rail-brace including a plurality of 20 bars, the terminal of one bar being formed with a groove which receives a tongue carried by the other bar, each of the bars being formed with an enlarged rail-engaging terminal, said terminals being formed with 25 openings which receive the securing devices which pass through the rail and the nuts which are arranged thereon.

In testimony whereof I affix my signature in presence of two witnesses.

HENRY E. GUYER. [L. s.]
